UNITED STATES PATENT OFFICE.

JOHN FESTA, OF BROOKLYN, NEW YORK.

GAS BURNER.

Application filed March 31, 1921. Serial No. 457,208.

To all whom it may concern:

Be it known that I, JOHN FESTA, a citizen of the United States, and residing at Brooklyn, Kings County, New York State, have 5 invented certain new and useful Improvements in Gas Burners, of which the following is a specification.

This invention relates to gas burners and more especially to that type of burners used 10 in connection with a mantle of incandescent material to produce a radiant effect, and the object of the invention is to provide a burner with a plurality of nipples which may all be used or a part of the whole used and the reduction of use will not interfere with the incandescent action of the fire clay, asbestos or 15 other similar material of which the mantle is composed.

These and other objects and details of the 20 invention are more fully described in the following specification, set forth in the appended claims and illustrated in the accompanying drawings, wherein:

Fig. 1 is a plan view of the burner.

Fig. 2 is a horizontal sectional view 25 through line 2—2 of Fig. 3.

Fig. 3 is a vertical sectional view through line 3—3 of Fig. 2.

Fig. 4 is a cross sectional view on the line 30 4—4 of Fig. 3.

Fig. 5 is a sectional detail of the cock.

In the use of gas heaters of the radiant type there is serious danger of incomplete combustion and consequently the appearance 85 of the lighted heater is seriously affected when the gas supply is reduced and the mantle ceases to be incandescent.

In the present invention the burner ports are so controlled that part of them may be 40 shut off entirely while the remainder receive a full supply of gas and the incandescent material will receive its necessary flame at that point.

As heretofore constructed burners of this 45 type could be turned down only to limit the gas supply and this would leave the heated material with less flame than necessary for incandescence, causing incomplete combustion and marring the appearance of the 50 heater.

In accomplishing these objects the burner comprises supply pipes 5 and 8, mixing tubes 6 and 7 and a vapor supply chamber 9, the latter having a plurality of nozzles 10 fitting 55 in openings 11 in the top of the tube and being located directly over tube 7.

A gas supply pipe 12 has the two-way cock 13 and the two branches 14 and 15 entering the respective mouths of the pipes 5 and 8, and each having an air shutter 16 that is 60 adjustable on its pipe to regulate the amount of air admitted to the tube.

It will be seen in Fig. 5 that the cock is so located as to supply an equal amount of gas to each pipe, but a quarter turn of the plug 65 closes one of the branches and leaves the other open as shown in Fig. 5.

In Figs. 2 and 3 it will be seen that the pipe 5 communicates with the tube 6 through the openings 17 and 18 at each end while pipe 70 8 communicates with tube 7 at the central opening 19.

Adjacent the tube 6 and beneath the supply tube 9 the tube 7 is divided so that the supply of gas from the pipes 5 and 8 are 75 separated by the partitions 20 at each end of the tube 7 and in the wall 21 that separates the latter tube from chamber 9 are openings 22 for the gas from pipe 5 while in that portion of tube 9 between the partitions 20 80 are openings 23 for gas from pipe 8.

Provisions are thus made by which the end nipples at each extremity of supply tube 9 are fed from pipe 5 while all of the intermediate nipples are supplied from pipe 8. 85

Any number of nipples that may be desired are separated and fed by the respective supply pipes but the arrangement shown provides a very harmonious grouping of jets to produce an agreeable lighting effect, either 90 as one central group or two end groups.

In case, therefore, that the temperature is reached in a room, the heat may be reduced so as to maintain an unvarying temperature to counteract the outside cold by turning the 95 cock 13 to cut off either one or the other of pipes 14 or 15.

It is obvious that the supply tube may be again divided to afford other variations, the cock being correspondingly altered, and that 100 the device may be otherwise modified and arranged without departing from the essential features above described or from the scope of the appended claims.

What I claim as new is:

1. In a gas burner, the combination of a plurality of gas supply pipes arranged besides each other horizontally, an elongated burner pipe parallel with and above the supply pipes and having nipples, partitions in 110 said burner pipe, a group of nipples adapted to communicate with a supply pipe, and an

intermediate pipe between the remaining nipples and the other supply pipe.

2. In a gas burner, the combination of a plurality of horizontally disposed gas supply pipes, an elongated burner pipe above the supply pipes and divided by partitions, nipples for the burner pipe, means affording communication between a central group of nipples with one of the supply pipes, and an intermediate pipe with chamber for the other supply pipe and adapted to deliver the gas to end groups of burners.

3. In a gas burner, the combination of a plurality of horizontally disposed gas supply pipes on the same plane, an elongated burner pipe on a plane above the supply pipes and divided by partitions into end and middle sections, a mixing tube beneath the

middle section and communicating with the latter and one of the supply pipes, a second mixing tube communicating with the end burner pipe sections and a second supply pipe, and burners for the various sections.

4. In a gas burner, the combination of a plurality of gas supply pipes comprising branches of a pipe, a two-way cock at the union of the branches, air shutters on the branches, a mixing tube for each branch, a supply tube having outlet nipples and division walls, and communicating tubes connecting the mixing tubes with separate divisions of the supply tube.

In testimony whereof, I have signed my name to this specification this 15th day of March 1921.

JOHN FESTA.
